INVENTOR
Max Freund
BY
Joseph L. Levy
his ATTORNEY

UNITED STATES PATENT OFFICE.

MAX FREUND, OF NEW YORK, N. Y., ASSIGNOR TO FREUND BROS. & CO., INC., OF NEW YORK, N. Y., A CORPORATION OF NEW YORK.

VANITY BOX.

Application filed November 21, 1923. Serial No. 675,988.

To all whom it may concern:

Be it known that I, MAX FREUND, a citizen of the United States, and a resident of the city, county, and State of New York, have invented a certain new and useful Improvement in Vanity Boxes, of which the following is a specification.

This invention relates to an improvement in a vanity box or case adapted for containing ladies' toilet articles, cosmetics, money and the like, and has for its object to provide an article of this character having a hinged mirror on the inner face of its cover, and means for holding said mirror at an angle to the cover and in an inclined position, while the cover is open and the contents of the box are accessible. This arrangement enables the mirror to be used while the box is resting on any suitable support and obviates the necessity of holding the box in one hand and on a level with the face when it is desired to use the mirror. In many forms of vanity boxes or cases in use at the present time, the inner face of the cover is provided with a fixed mirror. In such a case the user has to either bend over the mirror or else hold the box in such a position that the mirror can be used. By the use of my improvements the mirror is held at a suitable angle without the assistance of the user.

A further object of this invention is to provide a box or case of the character mentioned, with an auxiliary lock or catch so that the possibility of the contents of the box becoming lost due to the inadvertent opening of the main lock is avoided.

With these objects, and such other objects as may hereinafter appear, in view, I have devised the particular arrangement of parts set forth below, and more particularly pointed out in the claims appended hereto.

Reference is to be had to the accompanying drawings, forming a part hereof, in which—

Figure 1 is a perspective view of my improved vanity box;

Figure 2 is a sectional view on the line 2—2 of Figure 1, looking in the direction of the arrows;

Figure 3 is a sectional view on the line 3—3 of Figure 2, looking in the direction of the arrows;

Figure 4 is a sectional view on the line

4—4 of Figure 1, looking in the direction of the arrows;

Figure 5 is a plan view of the hinge of the brace member for the mirror;

Figure 6 is a sectional view on the line 6—6 of Figure 5, looking in the direction of the arrows; and

Figure 7 is a side elevation of a modified form of construction.

Throughout the various views of the drawings, similar reference characters designate similar parts.

In the embodiment of my invention as disclosed in Figures 1 to 6 inclusive, 1 indicates the bottom of the box, 2 indicates the ends; 3 the top or front, and 4 indicates the back. The cover is shown at 5 and to the front edge 6 of said cover is secured the latch portion 7 of the main lock 8, which is secured to the front strip 3 of the box.

At 9 is shown the usual handle by which the box is carried.

The cover 5 is hinged to the box by the hinge 10 and it will be noted that the portion 11 of said hinge which is secured to the upper edge of the back 4 of the box, is secured at an angle or is inclined (see Figure 2). This arrangement causes the cover 5 of the box to extend backward beyond a vertical position when in its raised position to counterbalance the mirror when said mirror is distended as will be hereinafter described.

The mirror just referred to is disclosed at 12 and the same may be of any suitable size and shape to fit within the cover 5. The mirror has its upper end hinged as at 13 to the inner face of the cover and adjacent the free or outer end of said cover. A foldable brace member connects the mirror 12 and the inner face of the cover 5, and said brace member consists of the two sections or strips 14 and 15 connected by the hinge 16. The strip 14 is secured to the back of the mirror 12, as at 18; and the strip 15 is attached to the inner face of the cover 5.

In Figures 1 and 2 the mirror is shown in its distended position where it will be seen that the same is held in such position by the brace composed of the members 14 and 15. To prevent said brace from collapsing downward at the hinge, a tongue 17 is provided, which bears against the section 14. When the mirror is in said distended position it lies

at an acute angle to the cover, and in a very convenient position to permit its being used without being in any way supported by the user. The mirror, when in its distended position, tends to pull the cover downward but such movement is counterbalanced by the cover which is held at a backward inclination due to the position of its hinge 10.

To close the mirror and place the same flat against the inner face of the cover 5, the brace member is folded upon its hinge 16 as shown in dotted lines in Figure 2, by pressure upon the mirror until said mirror swings flat against the cover where it is secured by means 15 of the interengagement of the snap-fastener members 19 and 20 secured on the inner face of the mirror and cover respectively.

A tab 21 is provided on the lower end of the mirror so that the same can be grasped 20 by the fingers and drawn out to its distended position.

In the modification of my invention disclosed in Figure 7, I make use of two brace members, one of which is located at each end 25 of the mirror. Each of said brace members consists of a pair of links 22 and 23 joined together by a hinge pin 24. The ends 25 of said links abut when the brace is extended and prevent downward collapse of the brace.

30 The auxiliary lock is shown in Figures 1, 2 and 3, where it will be seen that the same consists of a hook-shaped latch member 26 adapted to engage with the edge of a plate 27 secured on the inner face of the edge strip 35 6 of the cover. The latch member is secured on the end of a flat spring 28 which is secured to the inner face of the front piece 3 of the box by the pins 29. A stud 30 is secured to the spring 28 and said stud projects 40 through a suitable opening in the front section 3 of the box. Pressure on the stud 30 forces the spring 28 inwardly and disengages the latch member 26 from its connection with the plate 27 whereby the cover may be swung 45 open.

The importance of the auxiliary lock just described will be understood. The main lock 8 sometimes opens inadvertently and in a box of this character the cover swings open and 50 the contents of the box fall out. The auxiliary lock prevents the cover from being swung open until the stud 30 is pressed, so that the possibility of loss by the inadvertent opening of the main lock 8 is prevented.

55 When the auxiliary lock is used, the fastening members 19 and 20, which hold the mirror down flat against the inner side of the cover, may be dispensed with if desired, for the auxiliary lock will hold the cover closed until manually opened and the mirror cannot swing to its distended position inadvertently, for inadvertent opening of the cover will be prevented.

From the foregoing it is obvious that my 65 invention is not to be restricted to the ex-

act embodiment shown, but is broad enough to cover all structures coming within the scope of the annexed claims.

What I claim is:—

1. An article of the class described comprising a box having a containing compartment, a hinged cover therefor, a mirror hinged to the inner face of said cover adjacent the free end of the same, and a foldable brace member connecting the mirror and cover and adapted to hold the mirror above and away from the containing compartment and at an angle to the cover when the cover is in its open position. 75

2. An article of the class described comprising a box having a containing compartment, a hinged cover therefor adapted to lie at an acute angle to the box when said cover is in its open position, a mirror hinged to the inner side of said cover, means for holding said mirror flat against the inner side of said cover when the cover is closed, a foldable brace member for holding said mirror above and at a distance from the containing compartment so that the contents of said compartment are accessible while the cover is in its open position, and means for limiting the folding movement of said brace member in one direction when the mirror reaches the limit of its extended movement. 90 95

3. An article of the class described comprising a box having a hinged cover, a mirror hinged to the inner face of the cover adjacent its outer end, a foldable brace connecting said mirror and cover and adapted to hold said mirror at an acute angle to the cover when said cover is open, a hinge for said cover adapted to hold said cover at an acute angle to the box when said cover is in its open position, and co-operating snap fastener members on the cover and mirror for uniting the free end of said mirror with the inner face of the cover. 100 105

4. An article of the class described comprising a box having a hinged cover, a mirror hinged to the inner face of the cover, a foldable brace member connecting said mirror and cover, said brace member being adapted to hold the mirror at an angle to the cover when the cover is in its raised position and adapted to lie between the cover and the back of the mirror when the mirror is held flat against the cover, and co-operating fastener members on the cover and mirror for holding said mirror in its folded position against the cover. 110 115 120

5. An article of the class described comprising a box, a cover hinged thereto, a mirror on the inner face of said cover, a lock for said cover, and an auxiliary lock independent of the first-mentioned lock for holding the cover in its closed position. 125

6. An article of the class described comprising a box having a hinged cover, a lock therefor, an auxiliary lock independent of 130

the first mentioned lock having a latch member, said cover having a plate adapted to be brought into locking engagement with the latch member when the cover is closed, a 5 spring on which said latch member is secured, and a stud on said spring extending through the box and adapted to be manually pressed to free the latch from engagement with the plate on the cover.

10 7. An article of the class described comprising a box having a hinged cover, a mirror hinged to the inner face of the cover and means for holding said mirror at an inclined position relative to the cover when the cover is in its open position, the hinge for the 15 cover being secured to the box at an angle whereby the cover will lie at an angle to the box when in its open position to counterbalance the mirror.

Signed at the city, county and State of 20
New York, this 16th day of November, 1923.

MAX FREUND.
